Attorney, Agent, or Firm—Cushman, Darby & Cushman

[57] CLAIM

The ornamental design for sawhorse bracket, as shown and described.

DESCRIPTION

FIG. 1 is a perspective view of a sawhorse bracket; FIG. 2 is a top plan view of the sawhorse bracket; FIG. 3 is a front elevational view of the sawhorse bracket, the back view being a mirror image thereof; FIG. 4 is a side view of the sawhorse bracket, the other side being a mirror image thereof; and, FIG. 5 is a bottom view of the sawhorse bracket. The broken lines showing sawhorse legs are for illustrative purposes only and form no part of the claimed design.

FIG. 1

FIG. 2

FIG. 3

FIG. 4

FIG. 5

UNITED STATES PATENT AND TRADEMARK OFFICE
CERTIFICATE OF CORRECTION

PATENT : Des. 352,788
